UNITED STATES PATENT OFFICE.

JOHN C. SCHNEIDER, OF HUDSON, WISCONSIN.

THRASHING-MACHINE.

SPECIFICATION forming part of Letters Patent No. 274,395, dated March 20, 1883.

Application filed January 9, 1883. (No model.)

To all whom it may concern:

Be it known that I, JOHN C. SCHNEIDER, of Hudson, in the county of St. Croix and State of Wisconsin, have invented certain new and useful Improvements in Thrashing-Machines; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal vertical sectional view of my improved thrashing-machine. Fig. 2 is a top view of the separators. Fig. 3 is a vertical cross-section of the same. Fig. 4 is a detail top view of the pitmen operating the separators. Fig. 5 is a detail side view of the same; and Fig. 6 is a detail view, showing one of the endless screws feeding the grain to the discharge-chute and the unthrashed ears to the elevator carrying it back to the cylinder.

The same letters of reference indicate the same or corresponding parts in all the figures.

My invention has relation to thrashing-machines; and it consists in the improved construction and combination of parts of the separating and discharging mechanisms, as will be hereinafter more fully described and claimed.

In the accompanying drawings, the letter A indicates the casing or frame of the machine, containing the several operative parts.

B is the feed-hopper through which the grain is fed to the thrashing-cylinder, C and the beater D, which aids in beating the loose grain out of the straw as it passes under it to the separators. These separators consist of a series of long narrow screens, E, having longitudinal grooves F in their upper surface and slots or holes G in the bottom of these grooves, so that as the grain is shaken out of the straw it will roll into these grooves and fall down through the holes to the shoe. The screens E are fastened upon cross-pieces H by means of bolts I, passing through hollow sleeves J, raising the screens above the cross-pieces, excepting the two outside screens, which are fastened upon the upturned ends K of the cross-piece.

Between the screens E are long boards L, fastened edgewise upon uprights M, which again are fastened to a cross-piece, N, and the

cross-pieces H and N are operated by means of pitmen and arms in such a manner that the screens and the boards will have an alternating upward and rearward vibratory motion, by which the grain is shaken out of the straw, and the straw is at the same time carried rearward and out of the machine.

The pitmen and arms operating the screens and boards are shown in detail in Figs. 4 and 5, and consist of two pitmen, O, connected at one end to a shaft, P, which forms two sets of double cranks—two cranks at each end—and is journaled in the frame A and connected by suitable belting with the drive-shaft. The upper ends of the pitmen are hinged to the ends of the cross-piece H, and two arms Q are hinged at the same place with their upper ends, while they are pivoted at their lower portion upon bolts or pins R in the frame. The boxes of these pitmen and arms are preferably constructed in the same manner as the pitmen patented in the thrashing-machine for which Letters Patent No. 267,599 were granted to myself and Hans Christofferson on the 14th of November, 1882. The lower ends, S, of the arms Q extend beyond the pins R and rock in segmental plates T upon the frame as the crank-shaft revolves. Two spiral springs, U, are fastened in the ends of the plate T, and bear with their free ends against the sides of the end of the arm, cushioning its motion and taking up all jars. The pitmen O operate the screens, and similar pitmen, V, operate the boards L, in conjunction with the arms W, which are of the same construction as the pitmen, but pivoted upon pins X in the frame. The pitmen and crank-shaft operate the screens in the rear end of the machine, while the screens and boards are supported in the forward end of the machine by means of arms Y and Z, constructed and fastened in the same manner as the arms Q and W.

The thrashed grain falls upon an endless apron, a, and is carried to the cleaning-shoe b, which is operated by a bell-crank, c, and pitman d. As the grain passes from the shoe b it falls into a box, e, fastened in the bottom of the frame, in which moves an endless screw-conveyer, f, which carries the grain to the discharge-tube. The conveyer consists of a shaft, g, journaled in bearings in the ends of box e, and having a collar, h, at one end, inside the bearing. Upon

this shaft are placed sleeves *i*, having a spiral flange, *j*, and a notch, *k*, in one end and a projection, *l*, in the other end, which fits into the notch of the adjoining sleeve, the ends of the spiral flanges fitting to each other, so as to form one continuous flange. A nut, *m*, is screwed upon the other end of the shaft, inside the bearing, clamping the sleeves between it and collar *h*, so as to hold them firmly. In this manner, if part of the conveyer is injured by accident or wear, one or two sleeves may be removed and replaced with new sleeves without the necessity of replacing the whole conveyer. A similar conveyer, *n*, is placed at the bottom of the rear end of the frame, which conveys unthrashed heads and grain passed over the cleaner-screens to an elevator, *o*, which carries it to an inclined board, *p*, from which it falls into the feed-hopper and is thrashed again.

Having thus described my invention, I claim and desire to secure by Letters Patent of the United States—

1. In combination with the screens of a grain-separator, the crank-shaft *P*, pitmen *O* and *V*, and arms *Q* and *W*, substantially as shown and set forth.

2. The combination, with the screens in a grain-separator, of the crank-shaft *P*, pitmen *O*, arm *Q*, pivoted at *R*, and having short end *S*, segmental plate *T*, and spiral springs *U* at both ends, bearing with their free ends against the end *S* of arm *Q*, as and for the purpose shown and set forth.

3. In a grain-separator for thrashing-machines, the combination of the screens *E*, pivoted cross-pieces *H*, arms *V*, pitmen *O* and arms *Q*, pivoted boards *L*, placed edgewise, alternating with screens *E*, arms *Z*, and pitmen *V* and arms *W*, substantially as and for the purpose shown and set forth.

4. The combination, in a grain-separator, of the crank-shaft *P*, pitmen *O*, arms *Q*, springs *U*, pitmen *V* and arms *W*, screens *E*, and boards *L*, substantially as shown and set forth.

In testimony that I claim the foregoing as my own I have hereunto affixed my signature in presence of two witnesses.

JOHN C. SCHNEIDER.
